UNITED STATES PATENT OFFICE.

OLIVER P. LUETSCHER, OF PITTSBURGH, AND FLORENCE C. BIGGERT, JR., OF CRAFTON, PENNSYLVANIA.

METHOD OF ROLLING ZINC SLABS.

Application filed August 24, 1923. Serial No. 659,184.

To all whom it may concern:

Be it known that we, OLIVER P. LUETSCHER and FLORENCE C. BIGGERT, Jr., residing at Pittsburgh and Crafton, respectively, county of Allegheny, and State of Pennsylvania, have invented new and useful Improvements in Methods of Rolling Zinc Slabs, of which the following is a full, clear, and exact description.

- 10 The present invention relates broadly to metal working, and more particularly to a method adapted especially to the rolling of non-ferrous metals, such as zinc slabs, into thin gauge sheet or strip form.
- 15 At the present time, it is customary in the art to which this invention relates to take the zinc slabs as they are cast and pass the same to an annealing furnace in which they are raised to the proper temperature.
- 20 From the annealing furnace, the slabs are taken, two at a time, to a roughing mill. These are taken by the "rouger" who places them on the fore plate of an ordinary two high mill with their long dimensions
- 25 parallel to the axes of the rolls. The first slab is then pushed through the mill where it is caught by a "catcher" on the other side and lifted to the top of the upper roll. The "rouger" then passes the second slab
- 30 through the mill and takes the first slab from the "catcher" and drops it to the fore plate ready for the next pass between the rolls. This operation is repeated as many times as is necessary to roll the slabs to
- 35 the desired thickness, the rolls being screwed down between successive passes. The last pass is usually made with the two rough sheets, as the slabs have become by that time, placed one on top of the other and
- 40 rolled as one sheet.

Being hand work, this method of rolling is a laborious operation, requiring considerable time and the service of a number of men by reason of the fact that it is extremely difficult, if not impossible, by methods heretofore used, to produce slabs of sufficient size to make it possible to handle the same in other ways.

In the copending application of Oliver P. Luetscher, Serial No. 636,857, filed May 5, 1923, there is disclosed a method of forming perfect slabs having much greater dimensions than has heretofore been considered feasible, and of such weight that

45 they cannot be effectively handled manual-

ly. The production of slabs of this character has made it possible to improve the method of rolling in order to produce more uniform thin gauge sheets with a fewer number of manual operations, less waste, 60 and consequently at a reduced cost.

In the accompanying drawings, there is shown more or less diagrammatically, for purposes of illustration only, one embodiment of the present invention, it being 65 understood that the drawings do not define the limits of our invention, as changes may obviously be made therein without departing from the spirit of the invention or scope of our broader claims. 70

In the drawings,—

Figure 1 is a side elevation, partly broken away, illustrating a portion of an annealing furnace together with a portion of a rolling mill; 75

Figure 2 is a detail view of a portion of the furnace structure illustrated in Figure 1;

Figure 3 is a diagrammatic top plan view of a portion of the finishing mill; 80

Figure 4 is a side elevation of the construction illustrated in Figure 3;

Figure 5 is a side elevation, similar to Figure 3, illustrating a slightly modified form of the invention; 85

Figure 6 is a top plan view of a plate indicating in dotted lines one method of shearing the same to form blanks for strip rolling; and

Figure 7 is a similar view of one of the 90 blanks.

In carrying out the present invention, the slabs 2, which may have a weight well in excess of 100 pounds, making them too heavy to be effectively handled manually, may be 95 forced by suitable charging mechanism 3 onto the supporting rails 4 of an annealing furnace 5. The charging mechanism is operative to gradually force the slabs through the furnace towards the discharge 100 end thereof.

Heretofore it has been customary to take the smaller slabs as produced, load the same onto cars, and pass the cars through the annealing furnace. Due to the comparatively small mass of such slabs, it has been found necessary to add considerable heat thereto in the furnace. By the present invention, by reason of the increased size of the slabs, it has been found that sufficient 110

heat may be retained thereby so that in some cases it may be desirable to cool the same. For this purpose, the furnace may be provided with a series of shutters or doors 7 connected in any desired manner to a thermostatic operating mechanism 8, whereby when the temperature within the furnace exceeds a predetermined point, the shutters will be automatically opened to permit the passage of an increased amount of air to the furnace.

In cases, however, where a higher temperature is desired, this may be obtained by suitable burners or electrical heating means 9, the circuit to which may be controlled by the thermostat 8, as well understood in the art, so as to close the circuit when the temperature within the furnace falls below a predetermined point.

20 The slabs at the proper temperature are then successively withdrawn from the annealing furnace and passed in known manner to the table 10 of a three high mill 11. Preferably, this mill will be of the character in which the center roll is provided with means for raising or lowering the same to permit the entry of the slabs therebetween and insure the proper reduction thereof. The rolled slabs are received by 25 the table 12 and returned, as is customary in the art, until there is produced a sheet having the desired thickness.

The sheet after this rough rolling is in the form of a wide strip having a width 30 substantially equal to, or slightly greater than, the length of the original slab. This strip is then passed to rotary shearing means 13 by means of which both edges are trimmed to provide a sheet of the desired width. This strip, in this form, may 40 either be sheared into lengths for the formation of packs suitable for finishing by the present method, or coiled for transportation or storage, as may be deemed advisable.

45 Preferably, however, each individual sheet with its edges sheared and trimmed is carried from the rotary shear to a series of finishing mills 14 arranged in tandem. Each of these mills will give the sheet a 50 single pass, and their number, therefore, should be equal to the number of passes it is desired to give the sheet.

In rolling by this method, I have found it very desirable to provide means to maintain a tension on both the entering and delivery side of the mill. For this purpose, as shown in Figures 3 and 4, the mills may each be provided with wedge guides 15 on the entering sides and with a power driven 60 reel or coiler 16 at the delivery end of the mill. To the accomplishment of this end, each mill should preferably be driven by separate motor 17 to allow any desired speed ratio to be maintained between the 65 rolls of the different stands. In Figure 5

there is illustrated a slightly modified form of tension device 15' at the entering side of each mill.

In some cases it may be desirable to add or subtract heat to or from the sheet during the finish rolling thereof. For this purpose, there may be provided suitable heating or cooling means 18 between the successive roll stands. This means, where utilized for heating, may be broadly of the character disclosed in the copending application of Florence C. Biggert, Serial No. 607,454, filed December 16, 1922, or of any other desired construction.

In the event it is desired to produce a sheet having a width greater than the length of the initial slab, the slab may be passed through the mill cornerwise on the alternate diagonals for any desired number of passes. This process will have the further advantage of improving the texture of the metal, due to the cross rolling thereof, or the working in opposite directions.

The production of a single sheet of the character herein recited possess many advantages, not only in the ease of operation, as clearly pointed out, but in the fact that a uniform product is insured. Each sheet so produced may be cut into a series of individual pieces of a size suitable for forming a pack and an entire pack formed from a single sheet. In this manner, absolute uniformity, both as to thickness and temper, between the initial sheets of each pack is insured, and, therefore much greater uniformity in the finished product is made possible. Heretofore, where each sheet in the pack has been individually rolled, any error or variation in the sheets has been maintained throughout the entire rolling operation.

The present invention also lends itself admirably to the production of strips. In rolling strips, a rough rolled plate S, as shown in Figure 6, either with or without its opposite edges trimmed, may be cut into a series of strips or blanks B, as indicated by dotted lines. It will be apparent that during the formation of the sheet S, it was rolled generally in the direction of the arrows a. During the rolling of the blanks B to reduce them to the desired thickness, they will be rolled at substantially right angles to the direction of first rolling, as indicated generally by the arrow b. This forms a strip having a better texture than is produced by present methods, as there is rolling in both directions.

The present invention is particularly adaptable for use in connection with the rolling of non-ferrous metals, such as zinc, into thin gauge sheets. Such sheets ordinarily have a thickness less than one sixteenth of an inch ($\frac{1}{16}$ ") and it will be apparent that the value of the invention is

increasingly important as the thickness diminishes. The invention is, however, adaptable to the rolling of any sheets having a thickness of one eighth of an inch ($\frac{1}{8}$ ") 5 or less.

From the foregoing, it will be apparent that the present invention provides an improved method of rolling zinc by the utilization of heavier slabs than it has heretofore been possible to make. 10

Further advantages arise from the provision of a substantial continuous process for the rolling of zinc, whereby the amount of manual labor and the time required to effect the necessary rolling operations are both reduced. 15

Further advantages arise from a method by which it is possible to form a pack of sheets produced entirely from a single body 20 of metal having uniform thickness.

We claim:

1. In the method of rolling zinc slabs into thin gauge sheets, the steps consisting in forming a slab having a weight too great 25 to be effectively handled manually, reducing the same in a three high mill, trimming the edges of the rough sheet, and then reducing the rough sheet to the desired thickness by passing the same successively 30 through a series of finishing mills.

2. In the method of rolling zinc slabs into thin gauge sheets, the steps consisting in forming a slab having a weight too great to be effectively handled manually, reducing 35 the same in a three high mill, trimming the edges of the rough sheet, then reducing the rough sheet to the desired thickness by passing the same successively through a series of finishing mills, and effecting a heat inter- 40 change between said mills.

3. In the method of rolling zinc slabs into thin gauge sheets, the steps consisting in forming a slab having a weight too great to be effectively handled manually, reducing 45 the same in a three high mill, trimming the edges of the rough sheet, then reducing the rough sheet to the desired thickness by passing the same successively through a series of finishing mills, and maintaining a tension 50 on the sheet during its passage through all of said mills.

4. In the method of rolling zinc slabs into thin gauge sheets, the steps consisting in forming a slab having a weight too great to 55 be effectively handled manually, reducing

the same in a three high mill, trimming the edges of the rough sheet, and then reducing the rough sheet to the desired thickness by passing the same as an individual sheet successively through a series of finishing mills. 60

5. In the method of rolling non-ferrous metals, the steps consisting in forming a slab, and rolling the same into a rough sheet by alternate passes on different diagonals. 65

6. In the method of rolling non-ferrous metals, the steps consisting in forming a slab, rolling the same into a rough sheet, passing the same as an individual sheet 70 through a plurality of finishing mills, and maintaining tension both on the entering and exit sides of at least some of said mills.

7. In the method of rolling non-ferrous metals, the steps consisting in forming a slab, rolling the same into a rough sheet, 75 passing the same through a plurality of finishing mills, and maintaining tension both on the entering and exit sides of at least some of said mills.

8. In the method of rolling non-ferrous metals, the steps consisting in forming a slab, rolling the same into a rough sheet, passing the same through a plurality of finishing mills, maintaining tension both on the 80 entering and exit sides of at least some of said mills, and effecting a heat interchange between some of said mills.

9. In the method of rolling non-ferrous metals, the steps consisting in forming a sheet by passing a slab through a series of 90 finishing mills under tension, and coiling the sheet while under tension.

10. In the method of rolling non-ferrous metals, the steps consisting in forming a rough sheet, shearing the same to form a 95 plurality of sheets, superimposing said sheets to form a pack, and then rolling said pack.

11. In the method of rolling zinc, the steps consisting in rolling a slab to produce 100 a rough sheet, passing the rough sheet through a series of finishing mills, cutting the rough sheet into a series of sheets, superimposing said sheets to form a pack, and then rolling the pack.

In testimony whereof we have hereunto set our hand.

OLIVER P. LUETSCHER.
FLORENCE C. BIGGERT, JR.
